DESIGN FOR AN AUTOMOBILE STORAGE HORSE

Elwyne O. Shreffler, Manteno, Ill.

Application April 27, 1942, Serial No. 106,725

Term of patent 3½ years

To all whom it may concern:

Be it known that I, Elwyne O. Shreffler, a citizen of the United States, residing at city of Manteno, county of Kankakee, and State of Illinois, have invented a new, original and ornamental Design for an Automobile Storage Horse, of which the following is a specification, reference being had to the accompanying drawing, forming a part thereof.

Fig. 1 is a perspective view of an automobile storage horse showing my new design; Fig. 2 is a similar view thereof taken substantially at right angles of Fig. 1; Fig. 3 is a bottom plan view thereof on a reduced scale; Fig. 4 is a top plan view; Fig. 5 is a front elevational; and Fig. 6 is a side elevational view thereof on a reduced scale.

I claim:

The ornamental design for an automobile storage horse, substantially as shown.

ELWYNE O. SHREFFLER.
